United States Patent Office

Des. 194,380
Patented Jan. 8, 1963

194,380

REFRIGERATOR CABINET OR SIMILAR ARTICLE

Robert E. Munz, Jeffersontown, Ky., assignor to General Electric Company, a corporation of New York

Filed May 19, 1961, Ser. No. 65,243

Term of patent 14 years

(Cl. D67—3)

FIG. 3

FIG. 1

FIG. 2

FIGURE 1 is a front perspective view of a refrigerator cabinet or similar article embodying my new design;

FIGURE 2 is a cross section on the line 2—2 of FIGURE 1 in the direction of the arrows; and

FIGURE 3 is a cross section on the line 3—3 of FIGURE 1 in the direction of the arrows.

The side wall not shown is substantially the same as the side wall shown. The rear wall not shown is conventionally plain.

I claim:

The ornamental design for a refrigerator cabinet or similar article, substantially as shown and described.
